UNITED STATES PATENT OFFICE.

ALFRED T. FOWLES, OF DALLAS, TEXAS.

BOILER-STAND.

1,332,119.

Specification of Letters Patent. Patented Feb. 24, 1920.

Application filed June 13, 1919. Serial No. 304,043.

To all whom it may concern:

Be it known that I, ALFRED T. FOWLES, a citizen of the United States, residing at Dallas, in the county of Dallas and State 5 of Texas, have invented certain new and useful Improvements in Boiler-Stands, of which the following is a specification.

This invention has for its object to provide an improved boiler stand for supporting boilers equipped with such types of water heaters as that defined in my co-pending application for patent filed June 13, 1919, Serial No. 304,041, for water heater and the invention has for its primary object to provide a stand affording passages between the supporting ring of the stand and the boiler permitting a free circulation of the products of combustion for the burner utilized for heating the liquid contents of the boiler.

Another object of the invention is to so construct the improved boiler stand that the rim part thereof may be detached from the supporting legs and applied directly to 25 the usual supporting rim of conventional types of boiler stands thus affording the desired passages for the circulation of the products of combustion.

With these and other objects in view as 30 will appear as the description proceeds the invention comprises the novel features of construction, combination of elements and arrangement of parts which will be more fully described in the following specification and set forth with particularity in the claims appended hereto.

Figure 1 represents a top plan view of the improved stand,

Fig. 2 represents a bottom plan view 40 thereof the legs being removed,

Fig. 3 represents a vertical central sectional view through the supporting stand having the legs applied thereto, and,

Fig. 4 represents a side elevation, partly 45 in section, of the rim, the legs being removed and the rim portion applied directly to the top of the conventional type of stand.

Referring to the drawing in detail wherein similar reference characters designate 50 corresponding parts throughout the several views, the numeral 5 indicates the circular ring-like body of the support provided in its upper face with a circular groove 6 of such diameter as to receive the usual flange 55 of the bottom edge of conventional types of boilers. The inner wall of the groove is

preferably extended a distance above the top edge of the outer wall as indicated at 7 to provide a baffle while a series of vertically disposed ribs 8 are formed integral 60 with the circular body and extend transversely across the bottom of the groove, terminating a suitable distance below the relatively low outer wall of the groove and constituting a support for the boiler whereby the latter is maintained in spaced relation to the bottom wall of the groove affording a series of radial air passages through which the products of combustion and heated air may circulate. The exterior 70 portion of the circular body member is provided with a plurality of radially projecting lugs 9 having recesses 10 therein provided with internal screw threads and constituting sockets for the reception of legs 75 11 whereby the rim may be supported in elevated position upon the floor.

However, if it is preferred, the supporting legs 11 may be dispensed with and instead the circular body member may be 80 applied directly to the circular top member or rim 12 of a conventional type of boiler support 13 illustrated in detail in Fig. 4. In order to adapt the body member for application to this type of boiler stand, the 85 body member is provided with a depending flange 14 which is designed to rest directly upon the rim 12 of the stand 13 and is preferably of serpentine or irregular form at its lower edge thereby providing a series of 90 passages permitting the heated air and products of combustion to circulate freely between the body member and the rim 12 of the stand.

As stated, the boiler support is designed 95 for use in connection with water heaters of the type described in claims of my co-pending application for patent for water heater and when used in this connection affords passage for the heated air and products of 100 combustion both between the boiler and the supporting ring and between the supporting ring and the boiler stand, when the ring is used in connection with the type of stand 105 illustrated in Fig. 4. The extended inner 110 wall 7 of the ring causes the products of combustion to be deflected upon the bottom of the boiler preliminary to the passage of the products of combustion between the lower edge of the boiler and the bottom wall of the groove 6.

It is further evident that the circular

groove 6 constitutes a container for the reception of such condensation of water as may be deposited therein from the outer surface of the boiler and owing to the heated condition in which the ring body is maintained during operation of the heater the water is evaporated from the groove and thus disposed of without coming in contact with the burner.

10 What I claim is:

1. A boiler support including a substantially circular boiler supporting member provided with a groove for receiving the bottom edge of the boiler, and a plurality of upstanding ribs formed in the bottom of the groove to maintain the boiler in spaced relation to the ring and affording a series of passages.
2. A boiler support comprising a circular body member provided with a circular groove in the top portion thereof, the inner wall of the groove being extended a distance above the outer wall thereof to provide a baffle member, and a plurality of upstanding ribs formed internally of the groove and maintaining the boiler in spaced relation to the ring to afford a series of passages.
3. A boiler support including a circular body member, and a depending supporting flange carried thereby adapted to engage the top rim of a boiler stand and having an irregular bottom edge to provide a series of passages between the body member and rim.
4. A boiler support including a circular body member provided with a boiler receiving groove in the upper portion thereof, a plurality of upstanding boiler supporting ribs carried by the body member and maintaining the boiler in spaced relation thereto

to provide a series of passages, and a depending supporting flange carried by the body member having an irregular bottom edge to provide a series of passages.

5. A boiler support including a circular body member provided in the top portion with a boiler receiving groove, boiler supporting ribs formed internally of the groove for maintaining the body member in spaced relation to the boiler and to afford a series of air passages, and a plurality of detachable legs supporting the body member and adapted for removal to permit the body member to be applied to a boiler stand.

6. A boiler support including a circular body member provided in the upper portion with a circular groove for receiving a boiler, a plurality of upstanding ribs formed in the bottom of the groove for maintaining the body member in spaced relation to the boiler and to afford a series of passages, a depending supporting flange carried by the body member provided with an irregular bottom edge providing a series of passages between the body member and stand when the body member is applied to the supporting rim of a boiler stand, and a plurality of supporting legs detachably connected with the body member.

7. A boiler support including a substantially circular boiler supporting member provided with a boiler receiving groove adapted to receive the condensation of moisture from the outer surface of the boiler and upstanding boiler supporting ribs formed in the bottom of the groove.

In testimony whereof I affix my signature hereto.

ALFRED T. FOWLES.
